UNITED STATES PATENT OFFICE

MAX EMMETT MILLER, OF PADUCAH, KENTUCKY

APPARATUS FOR CUTTING AND PRINTING VENEER

Application filed January 24, 1929. Serial No. 334,758.

This invention relates to apparatus for cutting and printing veneer.

Heretofore in the manufacture of baskets and other articles formed of veneer, it has been necessary first to cut the veneer and thereafter, either prior to or following the formation of articles of veneer, to apply trade-marks and the like by means of rubber stamps operated by hand. This method of marking has been unsatisfactory because it is slow, frequently produces an unsatisfactory impression, and adds materially to the cost of production.

It is an object of the present invention to provide a mechanism whereby the cutting and printing operations can take place simultaneously so that the sheets of veneer, as delivered from the veneer lathe will bear the desired impressions that are subsequently to appear on the baskets or other merchandise produced from the stock.

Another object is to provide a printing mechanism adapted to be driven by the log acted on by the lathe, the printing mechanism being so constructed as to supply ink in proper quantities to the printing roll.

With the foregoing and other objects in view which will appear as the description proceeds, the invention resides in certain novel details of construction and steps of the method hereinafter more fully described and claimed, it being understood that changes in the precise embodiment of the invention herein disclosed may be made within the scope of what is claimed without departing from the spirit of the invention.

In the accompanying drawings the preferred form of the invention has been shown.

In said drawings,

40 Figure 1 is a front elevation of a veneer lathe having the present improvements combined therewith.

Figure 2 is a section on line 2—2, Figure 1.

45 Figure 3 is an elevation of one side of the printing mechanism.

Figure 4 is an elevation of the opposite side thereof.

50 Figure 5 is a plan view of the printing mechanism.

Figure 6 is a section on line 6—6, Figure 4.

Referring to the figures by characters of reference, 1 designates a veneer lathe of any ordinary construction provided with the usual knife 2 adapted to cut veneer from a log L mounted for rotation upon and supported by the lathe.

The printing mechanism associated with the lathe can be mounted in any manner desired. For example, standards 3 can be erected on the end portions of the lathe, these standards being connected at their upper ends by a cross strip 4. Brackets 5 may be extended from intermediate portions of the standards to support a cross rod 6.

In the structure illustrated two printing mechanisms have been shown but it is to be understood that any desired number can be used in connection with the lathe. As the two printing mechanisms illustrated are of the same construction, a description of one will suffice.

A lever 7 is fulcrumed on the rod 6 and one end portion thereof constitutes a handle 8 while the other end portion is connected to a rope 9 or other flexible element extending over a guide pulley 10 suspended from strip 4. The rope can be looped between the pulleys and provided with a ring 11 which, when placed in engagement with a hook 12 on the lathe structure, will support those ends of the two levers 7 to which the flexible element 9 is secured.

Secured to each lever 7 at that end remote from handle 8 is a yoke 13. A link 14 is pivotally mounted on the yoke at one side of lever 7 and a handle 15 is pivotally mounted on the yoke at the other side of the lever. Journaled between the link and one end of the handle is an ink spreading roll 16 which bears upon and is adapted to receive motion from a large ink distributing roll 17 journaled in the yoke 13 and provided with a pulley 18. A printing roll 19 is also journaled within the yoke but is supported below the distributing roll 17. A pulley 20 rotates with printing roll 19 and is operatively connected to pulley 18 by a crossed belt 21.

Interposed between the lower portions of the rolls 17 and 19 are small transfer rolls 100

22 and 23 the trunnions 24 of which are slidably mounted in slots 25 formed in the sides of the yoke 13. Springs 26 are attached to the sides of yoke 13 and have diverging springs 27 extending therefrom and connected to trunnions 24. Thus the transfer rolls are held normally pressed together yieldingly and also normally pressed against the rolls 17 and 19.

10 The transfer roll 22 is formed preferably of rubber composition while roll 23 is formed preferably of felt.

The weight of the several rolls and the parts associated therewith is sufficient to hold the printing roll normally applied with sufficient pressure to the periphery of the log L to print an impression thereon. When the lathe operates so as to cause rotation of the log in the direction indicated by the arrow in Figure 2 motion will be transmitted therefrom to the printing roll 19 which, in turn, will transmit motion through the belt 21 to the distributing roll 17. These two rolls will also cause the transfer rolls 22 and 23 to rotate and the spreading roll will also be actuated. Ink is applied to the spreading roll and transferred thereby to the distributing roll. Handle 15 is oscillated by the operator to cause reciprocation of the spreading roll and this will result in even spreading of the ink over the distributing roll. Rolls 22 and 23 will convey the ink to the printing roll so that the desired impressions will be made on the log immediately prior to the cutting operation.

35 When it is desired to place a log in or remove it from position the printing devices can be lifted by means of the rope 9 and these devices can be supported in raised position by placing ring 11 in engagement with hook 12. Obviously means other than that shown and described can be used for supporting the printing devices in inactive position.

40 By providing the handles 8 the printing rolls 19 can be pressed tightly against the periphery of the log by thrusting upwardly against the handles.

45 Veneer produced by a lathe equipped as herein described will be ready to be cut and shaped to produce baskets or other articles of merchandise each of which will display one or more of the impressions produced on the veneer by the printing mechanism.

50 What is claimed is:

55 The combination with a veneer lathe for supporting and rotating a log, of a lever pivotally mounted above and supported by the lathe, a handle in one end of the lever, printing mechanism at the other end of the lever for engaging and printing upon the periphery of the rotating log, said mechanism including an ink-spreading roller, and a handle for reciprocating the roller, the handle on the lever constituting means for transmitting thrust through the printing mechanism and 60 against the log, a flexible actuating element

connected to the lever adjacent to the printing mechanism, a guide for the intermediate portion of said element, and cooperating means on said flexible element and the lathe for holding the printing mechanism out of contact with the supported log.

65 In testimony that I claim the foregoing as my own, I have hereto affixed my signature.

MAX EMMETT MILLER.
